COMBINED PITCHER AND DISPENSING CLOSURE

Earl S. Tupper, Smithfield, R.I., assignor to Rexall Drug
and Chemical Company, Los Angeles, Calif., a corpo-
ration of Delaware

Filed Jan. 4, 1960, Ser. No. 58,917

Term of patent 14 years

(Cl. D58—26)

FIGURE 1 is a perspective view of a combined pitcher and dispensing closure embodying my new design;

FIGURE 2 is a side elevational view thereof; and

FIGURE 3 is a top plan view thereof.

The essential features of my design reside in the por-
tions shown in full lines.

I claim:

The ornamental design for a combined pitcher and
dispensing closure, substantially as shown and described.
